DISMOUNTABLE GUN MOUNTING

Fritz Herlach and Heinrich Herlach, Solothurn, Switzerland, assignors to Waffenfabrik Solothurn A.-G., Solothurn, Switzerland, a corporation of Switzerland

Application November 27, 1933, Serial No. 699,999
In Germany March 3, 1933

6 Claims. (Cl. 89—40)

In gun mountings which are adapted to be dismantled into separate loads in order to facilitate transport, it is essential that it should be possible for the dismantling and the assembling of the gun mounting for firing to be carried out rapidly and in a simple manner without the employment of special auxiliary devices in such a manner that as far as is practicable no damage can be done to the gun or to the equipment, and that the gun crew is not exposed to danger.

The units of such a mounting must be so interconnected as to prevent involuntary detachment, and it is advantageous by means of interlocks between the different safety devices to ensure that the units can be dismantled and assembled only in a definite, obvious sequence; and parts which are very liable to be lost, such as coupling pins, screws and nuts, should be dispensed with as far as is practicable.

The invention relates particularly to carriages comprising a cradle carrying the gun and trunnioned in a training saddle so as to be capable of elevation within a predetermined range. According to the invention the trunnion bearings which are made separate for the dismantling and assembling of the cradle, are prevented from opening by locking members which in their turn cannot be disengaged until the completion of a swinging movement of the cradle out of its locked position, beyond the normal range of elevation for the gun and which movement breaks the elevating gear connection.

Further the cradle can be removed from or fitted on the saddle only when it is in a position in which the elevating gear connection from one part to the other is broken and also when any spring elevation compensators provided have become ineffective.

The cradle cannot be removed within the normal range of elevation provided for firing the gun. In the construction according to the invention an unintentional excess of this permitted elevation is prevented by an elevation limiting stop rendered operative by the mounted gun. Then the cradle cannot be moved into the dismantling position and dismantled until the gun has been removed therefrom.

Further appropriate details of the invention are explained by means of the accompanying drawings which show an example of construction of a gun mounting.

In the drawings:—

Fig. 1 is a general view of the gun mounting in elevation;

Fig. 2 is the same view on an enlarged scale, in

partial section through the trunnions and their connecting members;

Fig. 3 shows a plan of the gun mounting;

Fig. 4 is a side elevation along the line C—D of Fig. 2;

Fig. 5 is a representation according to Fig. 2 with the cradle swung into the dismantling position.

A saddle 1 capable of being trained through 360° has trunnioned therein a cradle 2 for carrying the gun, by means of trunnion pins 3 integral with the cradle 2. Elevating gear 4, 5 capable of elevating the barrel through a normal range of about 85° is provided between the cradle and the saddle. The trunnion pins 3 of the cradle 2 are mounted in lower half bearings 6 on the saddle 1 and are secured against rising by covers 7. The covers 7 have, when seen from the side, a spectacle-like shape with a bridge member which engages over the trunnion pin 3, and the eyes 8, 9 or 8', 9' (Fig. 3) engaging forkwise around bearing bosses 10, 11 on the saddle 1 located one on each side of the trunnion (Figs. 2 and 3). The three parts 8, 9, 10, together with a bolt 12 form a hinge joint about which the cover 7 with its eyes 8, 9' is adapted to be pivoted. In the latter pair of eyes there is mounted a bolt 13 which is cut away in semi-circular cross-section and is adapted to be turned by means of a side handle 14.

The bearing 11 (Fig. 2) has a three-quarter circle bearing surface and through the cut-away quadrant 11' is inserted the bolt 13 movable by means of the handle 14 into the position shown in Fig. 5, and which by rotation through about 90° serves as a bolt to prevent the cover from rising. In order that this bolted position may be secured, the handle 14 is adapted to be fixed by a spring catch 15 (Figs. 3 and 2).

Further, the opening and closing of the cover 7 are prevented by a bolting device which requires elevation of the cradle 2 beyond the normal range of elevation of the gun, in order to permit the swinging movement of the handle 14 to release the bolt 13. This bolting device consists of a collar 3' extending over the greater part of the periphery of the trunnion pin, which collar does not permit the handle 14 to be unbolted until the recess 3'' of the collar 3' is disposed opposite the end 14' of the handle facing the collar 3' (Fig. 5). The elevation of the cradle 2 necessary for this is normally hindered by an elevation stop, as shown in Fig. 4, when the gun mounting has been assembled for firing.

By the insertion of the gun 16 (the outline

of which has been indicated in Fig. 4 by chain lines) in the cradle 2 in which it is secured by a removable clamping hook 17, a double-armed lever 18 pivotally mounted about a bolt 18' in the cradle 2 is swung out sideways to such an extent that when the barrel is elevated about 85° it comes into contact with a stop 1' on the saddle and prevents the further elevation of the barrel.

If the cradle 2 is to be dismounted, first of all 10 the gun 16 must be removed and the cradle 2 must be swung upwards into a position beyond the elevating range, in which the recess 3'' of the trunnion collar 3' is disposed opposite the lever projection 14' and the handle 14 can be 15 turned to release the bolt 13 and open the cover 7.

In this dismounting position of the cradle 2 shown in Fig. 5, the elevating toothed segment 4 fixed thereto is disengaged from the pinion 5 20 (see Fig. 1) so that it is impossible for the gear teeth to be damaged during dismantling or assembling.

Further, the compensating springs accommodated in the dash-pots 19 and engaging on the 25 one hand with these and on the other hand with the trunnion ends enclosed thereby, are now relaxed so that the projections 19' of the dashpot resting on the pin 1'' in the cradle 1 are not loaded by the compensating springs and automatically give an unhindered slight turning of 30 the dash pots 19, such as is necessary for disengaging the projections 19' from the pins 1'' which they partially surround, when the cradle is lifted out of the trunnion bearings.

35 We claim:—

1. A dismountable gun carriage for mounting a gun comprising a cradle in which the gun is mounted, a saddle, trunnions about which the cradle and gun can be elevated in the saddle, 40 said trunnions including trunnion pins and separable upper and lower bearing members surrounding said pins, a gear for elevating the gun and cradle through a predetermined angular range, locking means normally securing the upper and lower trunnion bearing members together, and means operable only when the gun cradle is elevated beyond the normal range for 45 effecting a release action of said locking means whereby the bearing members can be separated to enable the cradle to be removed from the saddle.

2. A dismountable gun carriage for mounting a gun comprising a cradle in which the gun is mounted, a training saddle, trunnions about 55 which the cradle and gun can be elevated, said trunnions including trunnion pins and separable upper and lower bearing members surrounding said pins, a gear for elevating the gun and cradle through a predetermined angular range, locking means operable to secure said upper and lower trunnion bearings together, means for operating the lock, and means on the trunnion pins for preventing an unlocking operation of the lock 60

except when the gun cradle is elevated beyond the normal range.

3. A dismountable gun carriage for mounting a gun comprising a cradle in which the gun is removably mounted, a saddle, trunnions about 5 which the cradle and gun can be elevated in the saddle, said trunnions including trunnion pins and separable upper and lower bearing members surrounding said pins, a gear for elevating the gun and cradle through a predetermined angular range, a stop determining the maximum angle of elevation, means rendering said stop inoperative upon removal of the gun from the cradle, locking means for normally securing the upper and lower trunnion bearing members together, and means operable only when the gun cradle is elevated beyond the normal range for effecting a release action of said locking means whereby the bearing members can be separated to enable the cradle to be removed from the 20 saddle.

4. A dismountable gun carriage for mounting a gun comprising a cradle in which the gun is removably mounted, a training saddle, trunnions about 25 which the cradle and gun can be elevated, said trunnions including trunnion pins and separable upper and lower bearing members surrounding said pins, a gear for elevating the gun and cradle through a predetermined angular range, a stop determining the maximum angle 30 of elevation, means rendering said stop inoperative upon removal of the gun from the cradle, locking means operable to secure together said upper and lower trunnion bearings, means for operating the lock, and means on the trunnion 35 pins for preventing an unlocking operation of the lock except when the cradle after removal of the gun therefrom is elevated beyond the then inoperative stop.

5. A gun carriage according to claim 2, in 40 which the locking means comprise eye members on the upper and lower trunnion bearing members, bolts having flattened portions extending through said eye members to secure the upper bearing members to the lower bearing members, 45 means for rotating said bolts to bring their flattened portions into register with openings in certain of the eye members whereby the upper and lower bearings can be separated to release the trunnion pins from the bearings, and collars on 50 the trunnion pins for preventing such rotation of the bolts when the angular movement of the trunnion pins corresponds to cradle elevation within the normal range.

6. A gun carriage according to claim 3, in 55 which the elevation stop comprises a lever pivoted in the cradle and cooperating with the gun, a projection on the saddle lying in the path of said lever to determine the range of elevation of the cradle in said saddle, and a spring cooperating with the lever to retract the same from said path when the gun is removed from the cradle.
